UNITED STATES PATENT OFFICE.

EDWIN G. NICEWANER, OF PITTSBURG, PENNSYLVANIA, ASSIGNOR OF
ONE-HALF TO ALEXANDER REED, OF NEW YORK, N. Y.

THEATER-CURTAIN-OPERATING MEANS.

SPECIFICATION forming part of Letters Patent No. 783,587, dated February 28, 1905.

Application filed February 6, 1904. Serial No. 192,367.

To all whom it may concern:

Be it known that I, EDWIN G. NICEWANER, a citizen of the United States, residing at Pittsburgh, in the county of Allegheny and State of Pennsylvania, have invented a new and useful 5 Theater-Curtain-Operating Means, of which the following is a specification.

This invention relates more particularly to means for lowering the asbestos or other fireproof curtain of a theater to cut off communication between the stage and body of the house; and the object is to provide means which may be immediately thrown into operation when an emergency requires it, said means automatically and positively lowering the curtain to the floor of the stage, thereby avoiding any chance of its binding or sticking, as may occur with curtains which descend simply under their own weight.

20 The preferred embodiment of the invention is illustrated in the accompanying drawings; but it will be understood that changes may be made in the construction shown without departing from the spirit of the invention.

25 In the drawings, Figure 1 is a sectional view through a portion of a stage, showing the proscenium-arch, the curtain, and the means for lowering said curtain. Fig. 2 is a detail view, on an enlarged scale, of one of the 30 lower corners of the curtain. Fig. 3 is a top plan view of the motor preferably employed. Fig. 4 is a sectional view through a theater, showing the controlling means for the motor located at different places therein.

35 Similar reference-numerals indicate corresponding parts in all the figures of the drawings.

The stage, as usual, includes the floor, (designated 4,) over the front of which extends 40 the proscenium-arch 5. The fireproof curtain is shown at 6, said curtain being suspended above and in rear of the arch and movable downwardly across the same to the floor of the stage. The curtain is of sufficient 45 width to overlap the sides of the arch and may be elevated by any suitable means—as, for instance, wrapped upon a roller 7, to which

is attached a handle-crank 8 for revolving the roller, and thereby elevating the curtain.

Suitably supported, preferably beneath the 50 central portion of the stage-floor 4, is a motor 9, that may be of any type desired, but is preferably a rotary hydraulic motor. This motor has a discharge 10, which may be connected to a sewer or other desirable waste-receiving receptacle. An inlet-pipe 10^a for furnishing the motive-supply fluid connects with this motor and in turn is connected with various conduits 11 and 12. The conduits 11 extend to opposite sides of the stage and in 60 rear of the proscenium-arch are provided with upstanding elbow portions 13, containing controlling-valves 14. The pipes 12 are extended to various parts of the theater—as, for instance, the balconies, box-office, or other desirable points—where they are provided with suitable controlling-valves 12^a, all of said pipes being connected with a body of fluid under pressure, preferably, perhaps, water, as the pipes and various connections are not as subject to fire and are usually located in places more protected against the same. A drum 15 is associated with the motor 9 and includes a clutch 16, constituting a detachable connection between said drum and motor. The drum 75 may be disconnected from the motor by suitable means—as, for instance, a lever 17 and is normally and automatically connected through the medium of a spring 18. Cables 19, attached to and capable of being wrapped 80 upon the drum 15, extend in opposite directions beneath the floor 4 and pass above idler-pulleys 20, journaled beneath the floor in line with the opposite lower corners of the curtain 6, which curtain is preferably provided with 85 outstanding ears 21. The cables 19, passing about the pulleys 20, extend upwardly in line with said ears and just behind the proscenium-arch, their upper ends being connected with bolts 22, that are slidably passed through the 90 ears 21 and are held elevated by suitable springs 23, coiled thereupon.

Under ordinary conditions it will be understood that the curtain is held elevated and in

active; but should a fire break forth upon the stage or in any part of the house any one by operating one of the valves will permit the passage of fluid through the conduit controlled thereby, which fluid passing into the supply-pipe 10^a will enter the motor and set the same in operation. As already described, the drum is normally clutched to the motor, and consequently said drum will be thrown into operation, wrapping thereupon the cables 19 and positively drawing the curtain downwardly across the arch to the floor of the stage. This movement will be accomplished without regard to the friction of the curtain against the arch or other elements, and when it has descended to its lowest position the motor will simply become stalled. In order, however, to prevent too great shock to the parts, the coiled springs 23 are employed, which thus offer a yielding resistance to the pull of the cables. After the curtain has been lowered and it is desired to raise it again the drum may be unclutched from the motor and the curtain elevated by means of the handle-crank 8 or any other suitable mechanism. Thus it will be seen that the objects mentioned in the preliminary portion of the specification are obtained, and while the apparatus has been shown and described in great detail it will be understood that numerous changes may be made without departing from the spirit of the invention as set forth in the claims hereto appended.

Having thus described my invention, what I claim as new, and desire to secure by Letters Patent, is—

- 35 1. The combination with a curtain, of means for raising the curtain, and a motor having a draft connection with the curtain for positively drawing the same downwardly.
- 40 2. The combination with a curtain, of means for raising the curtain, and a motor having draft connections with the opposite lower end portions of the curtain for positively drawing the same downwardly.
- 45 3. The combination with a stage and proscenium-arch, of a curtain movable downwardly across the front of the stage and overlapping the opposite sides of the arch, a motor, and draft-cables connecting the motor and the opposite lower end portions of the curtain for positively drawing said curtain downwardly.
- 55 4. The combination with a stage including a floor and proscenium-arch, of a curtain movable downwardly across the front of the stage and overlapping the opposite sides of the arch, a motor located beneath the floor and having a drum, cables connecting the drum and the opposite lower end portions of the curtain for lowering said curtain, and means for controlling the movement of the motor.
- 60 5. The combination with a stage including a floor and proscenium-arch, of a curtain movable downwardly across the front of the stage

and overlapping the opposite sides of the arch, 65 a motor located beneath the floor and having a drum, cables connecting the drum and the opposite lower end portions of the curtain for lowering said curtain, and means for controlling the movement of the motor, said means being located on the stage on opposite sides of the arch.

6. The combination with a stage including a floor and a proscenium-arch, of a curtain suspended above the arch and movable downwardly across the same, said curtain overlapping the sides of the arch, a fluid-motor, means for conveying fluid to the motor, a plurality of independently-movable controlling devices for said fluid-motor, a drum having a connection with the motor, and cables connected to the opposite lower corners of the curtain and wrapped upon said drum.

7. The combination with a stage including a floor and a proscenium-arch, of a curtain suspended above the arch and movable downwardly across the same, means for elevating the curtain, a fluid-motor located beneath the floor and having a discharge, independent supply-conduits leading to the motor, independent controlling devices constituting parts of said conduits, cables secured to the opposite lower corners of the curtain and extending downwardly in rear of the arch, pulleys journaled in line with said corners of the curtain, 95 said cables passing about the pulleys, and a drum having a connection with the motor, said cables being wrapped upon the drum.

8. The combination with a stage and proscenium-arch, of a curtain movable downwardly 100 across the front of the stage and overlapping the opposite sides of the arch, a motor, cables connected to the motor, and yielding connections between the cables and the curtain.

9. The combination with a stage and proscenium-arch, of a curtain movable downwardly across the front of the stage and overlapping the side edges of the arch, a motor, a drum having a detachable connection with the motor, and cables connecting the drum and the curtain, said cables extending upwardly alongside and in rear of the proscenium-arch.

10. The combination with a stage and proscenium-arch, of a curtain movable downwardly 115 across the front of the stage and overlapping the sides of the arch, a motor, a drum having detachable connections with the motor, a spring for normally holding the drum in connection with the motor, and cables connecting the drum and curtain.

11. The combination with a theater having an auditorium and a stage, of a curtain for separating the stage and auditorium, a motor having a connection with the curtain for positively lowering the same, and separate devices located at different points about the theater for controlling the operation of the motor.

12. The combination with a theater having

an auditorium and a stage, of a curtain for separating the stage and the auditorium, a motor having a connection with the curtain for positively lowering the same, and separate devices located on the stage and throughout the auditorium for controlling the operation of the motor.

In testimony that I claim the foregoing as my own I have hereto affixed my signature in the presence of two witnesses.

EDWIN G. NICEWANER.
